E. WALTER.
DEVICE FOR ROLLING CYLINDRICAL BODIES.
APPLICATION FILED JAN. 5, 1917.

Patented July 16, 1918.

UNITED STATES PATENT OFFICE.

ERNEST WALTER, OF BELLEVILLE, NEW JERSEY, ASSIGNOR TO VERONA CHEMICAL COMPANY, OF NEWARK, NEW JERSEY, A CORPORATION OF NEW JERSEY.

DEVICE FOR ROLLING CYLINDRICAL BODIES.

1,272,739.

Specification of Letters Patent. Patented July 16, 1918.

Application filed January 5, 1917. Serial No. 140,676.

To all whom it may concern:

Be it known that I, ERNEST WALTER, a citizen of the United States, and a resident of Belleville, county of Essex, and State of New Jersey, have invented certain new and useful Improvements in Devices for Rolling Cylindrical Bodies, of which the following is a specification.

This invention relates to a device for rolling barrels and is adapted for use in plants and establishments where cylindrical bodies, such as barrels, drums, tanks and the like, are moved about both empty and filled, and sometimes for comparatively long hauls where the places in the plant from and to which the barrels must be moved are separated by a considerable distance. It is customary at present to either roll the barrel along the ground by manual labor, which is somewhat intermittent and slow and requires considerable labor, another way being to use a carriage heavy enough to support a barrel or drum and rolling the barrel by means of skids or an inclined way onto the carriage. This also requires considerable manual labor, taking usually two or three men in case of a full barrel, and more in the case of larger sized drums which are filled with liquid. These above described methods at present in use are expensive and slow.

My invention relates to a device which moves the barrel without lifting it from the ground and that provides means for its steady rolling, since the force is applied by means of the device so that the friction is minimized and the rolling of the barrel is thus made steady and comparatively quick.

The invention is further designed to provide a device of this kind which is easily portable, not being necessarily strong enough or heavy enough to support a barrel, but being in turn supported by the barrel when it is in place and acting to prevent any material relative movement between the carriage and the barrel while the carriage or frame is in position on the barrel.

Another object of the invention is to provide a device of this kind in which the rollers that engage the barrel, when the device is on the barrel, can also be used for supporting the device so that it can be easily rolled along the ground when the device is not on the barrel.

The invention is adapted for wooden bar-

rels and the like, but is more particularly adapted for heavy metal containers, such as are used in chemical plants and similar establishments, which even when empty have considerable weight, but when full are very hard to move by hand.

It will be understood in this specification that the device is described as being applied to a barrel, but this is simply for the purpose of making the description clear, since the device can be used on any form of cylindrical body that is to be moved along the ground by rolling it without necessarily lifting it.

The invention is illustrated in the accompanying drawing in which one embodiment of the invention is shown, it being understood, however, that different forms of the device may be used and the parts differently disposed to bring about the same result, but the embodiment that is illustrated shows one of the preferred forms of the device.

In said drawing, Figure 1 is a plan view of one form of frame, the view illustrating the frame in place on a barrel, and Fig. 2 is a side view of the construction illustrated in Fig. 1.

The device primarily consists of a carriage or frame that is constructed with rollers to minimize the friction between the device and the barrel when the device is placed over a barrel. The device when on a barrel being preferably suspended from contact with the ground and having means thereon whereby the barrel, or other cylindrical body on which the device is supported, can be moved. In the form shown the frame comprises side portions or members, these side portions each having a beam 10 which is a draft beam in the form illustrated, the side portions having means for supporting an upper roller or rollers, such means, in the form shown, consisting of brackets on each side portion, each bracket comprising an inclined beam 11 and a substantially vertical beam 12, thus providing a triangular side portion which, with the opposite triangular side portion, provides a means for supporting several of the rollers. The rollers 13 and the rollers 14 are fixed in the sense that they are arranged in the frame so that they have no movement relative to each other, these rollers being arranged respectively on the axles 15 and 16, being held

against movement on the axles by suitable collars 17, the rollers themselves being free to revolve freely on the axles. These rollers can be disposed the proper distance apart in 5 a lateral direction, but for steadyng the barrel and for providing the best traction they are preferably arranged near the side beams so that they engage the barrel adjacent to the heads of the barrel. It will thus 10 be readily seen that when the frame is pulled by suitable traction means, the draft beams 10 and the bracket supported thereon push on the barrel through the axles and the rollers aforesaid and the barrel is rolled 15 along the ground, since this pressure from the rollers 13 and 14 is applied in rear of the point of rolling contact 18 of the barrel 19. Any suitable means for moving the device can be employed, man power being 20 used in the case of small barrels, but in the case of the larger cylindrical bodies, a horse is preferably employed which can be attached by suitable harness, the view illustrating strands 20 connected by rings 21 to 25 the draft beams 10, but any other form of attachment can be used, as will be understood.

To permit a barrel that is being moved forward to be stopped, and to provide for 30 moving a barrel backward, and also to provide a positive means for holding the carriage on a barrel, and as a still further means for providing for the removal and installation of the device on a barrel, I provide a third set of rollers 22, the rollers 22 being arranged to rotate freely on an axle 23, which axle is adjustable so that the distance between the rollers 13, 14 and 22 can 35 be varied so as to fit different sizes of barrels. One form of adjustment is shown, this comprising perforations 24 in the draft beams 10 which, in the form shown, are made of angle iron, these perforations being all of them adapted to receive the ends 40 of the axle 23, a collar 25 and a pin 26 being used to prevent any sliding movement of the axle 23 in the perforations 24. When the rollers 22 are to be moved to permit the device to be either put on or taken from a 45 barrel, or to provide an adjustment for a different size of barrel, the ends of the draft beams 10 are slightly sprung apart after the pin 26 has been removed, this springing being sufficient to clear the ends of the axle 23, then the axle can be moved into any of the holes 24 and after the axle is fitted in the proper hole the draft beams 10 are permitted 50 to resume their original positions, the pin 26 is replaced in the position shown in the drawing, and the adjustment is complete. It will thus be readily seen that the rollers 22 and 14 can be used to provide traction for the device when it is not on a barrel, all the rollers of the device, however, 55 cooperating for supporting the device 60 65

on a barrel, the rollers embracing the barrel so that it can be moved backward or forward according to which direction the carriage is moved, and the rollers being arranged to bear on the barrel both in rear and in front 70 of its rolling point of contact with the ground, provide a means for bringing about these functions.

Many different forms of device can be made without departing from the scope of 75 the invention, but the form shown embodies features of advantage, the axles in this case serving to connect and also to separate the side frames or portions, particularly the axles 15 and 16 which are preferably attached to the side frames by means of the nuts 27 screwing on the screw-threaded ends 28 of the axles 15 and 16.

The number of rollers on each axle can be varied, but I prefer to arrange two on each 85 axle as shown, being separated far enough to make it easy to change the direction of the barrel slightly or to cause it to turn a corner, this being possible on account of the independent motion of each roller on its 90 axle.

Having thus described my invention, I claim:

1. A device for rolling barrels comprising a frame consisting of side portions, the side 95 portions having draft beams; a fixed axle at one end of the draft beams, rollers on the fixed axle, a second axle on the side beams and adjustable toward and from the fixed axle, and rollers on the adjustable axle. 100

2. A device for rolling barrels comprising a frame having draft beams at the sides, brackets on the draft beams, rollers supported from the draft beams and the brackets, the side beams being perforated, an axle 105 removable from the perforations, rollers on the removable axle, and means for fastening the removable axle in the perforations.

3. A device for rolling barrels comprising a frame having draft beams at the sides, 110 brackets on the draft beams, rollers supported from the draft beams and the brackets, the side beams being perforated and adapted to be slightly sprung apart, a removable axle in the perforations, rollers on the removable axle, and means for securing the axle into place and the beams against springing.

4. A device for rolling barrels comprising a frame provided at its forward end with an 115 axle and a pair of rollers on said axle, and provided at its rearward end with an axle and a pair of rollers thereon, the axle of the forward pair of rollers being adjustable toward and away from the rear axle, and 120 rollers on said frame received above the first and second sets of rollers, all of said rollers being adapted to engage a barrel by the periphery thereof and to receive the barrel bodily therebetween. 125 130

5. A device for rolling barrels comprising a frame provided at its forward end with an axle and a pair of rollers on said axle, and provided at its rearward end with an 5 axle and a pair of rollers thereon, and rollers on said frame received above the first and second sets of rollers, all of said rollers being adapted to engage a barrel by the periphery thereof and to receive the barrel bodily therebetween. 10

In testimony that I claim the foregoing, I hereto set my hand, this 2nd day of January, 1917.

ERNEST WALTER.
